(57) **CLAIM**

The ornamental design for a tire tread, as shown and described.

DESCRIPTION

FIG. 1 is a perspective view of a tire tread of a tire of a first embodiment of the present application;

FIG. 2 is a front view of the tire of FIG. 1;

FIG. 3 is a side view of the tire of FIG. 1;

FIG. 4 is a perspective view of a tire tread of a tire of a second embodiment of the present application;

FIG. 5 is a front view of the tire of FIG. 4;

FIG. 6 is a side view of the tire of FIG. 4; and,

FIG. 7 is an enlarged, partial perspective view of FIG. 1.

The broken lines and the region there between defining the sidewall region between the bead and the tread, depict subject matter that forms no part of the claimed tire tread design, and are included for the purpose of illustrating the full tire.

The tread pattern is understood to repeat throughout the circumference of the tire. The side views of FIGS. 3 and 6 are the same for each side of the tires of FIGS. 1 and 4, respectively.

1 Claim, 7 Drawing Sheets
